*Primary Examiner—Jeffrey Asch
Attorney, Agent, or Firm—Charles L. Moore***[57] CLAIM**

The ornamental design for a portable communications device, as shown and described.

DESCRIPTION

FIG. 1 is a top, front and right side perspective view of a portable communications device showing our new design in a closed position;

FIG. 2 is a front elevational view thereof;

FIG. 3 is a right side elevational view thereof;

FIG. 4 is a left side elevational view thereof;

FIG. 5 is a top plane view thereof;

FIG. 6 is a bottom plane view thereof;

FIG. 7 is a rear elevation view thereof;

FIG. 8 is a top, front and right side perspective view showing our new design in an open position with the flip member in one position;

FIG. 9 is a right side elevation view thereof;

FIG. 10 is a left side elevation view thereof;

FIG. 11 is a front elevation view thereof;

FIG. 12 is a top, front and right side perspective view showing our new design in an open position with the flip member in another position;

FIG. 13 is a top, front and right side perspective view showing our new design in an open position with the flip member in further position; and,

FIG. 14 is a left side elevation view showing our new design in an open position with the flip member in a still further position.
